UNITED STATES PATENT OFFICE.

WILLY SARTIG, OF ESSEN, GERMANY, ASSIGNOR TO FRIED. KRUPP AKTIENGESELLSCHAFT, OF ESSEN-ON-THE-RUHR, GERMANY.

OVERLOAD-CIRCUIT BREAKER FOR MOTORS STARTED BY MEANS OF A STARTING RESISTANCE.

Application filed March 10, 1922. Serial No. 542,736.

To all whom it may concern:

Be it known that I, WILLY SARTIG, residing at Essen, Germany, a citizen of the German Republic, have invented a certain new and useful Improvement in Overload-Circuit Breakers for Motors Started by Means of a Starting Resistance, of which the following is a specification.

This invention relates to improvements in overload circuit-breakers which are designed to protect electric motors from overload and the sensibility of which varies automatically during the starting of the motor to be protected, such as disclosed for example in the application for Letters-Patent of the United States filed December 29, 1921, Serial No. 525,695 in the name of Felix Tobien.

The present invention has for its object to provide an overload circuit-breaker of this character the sensibility of which is increased as long as a body which is moved on a prescribed track by the electric motor to be protected, is within a definite section of this track.

The invention is especially adapted for use on electrically driven vehicles or cranes which should travel at reduced speed on one or more sections of their track.

With the aforesaid end in view the invention consists in the arrangement, construction and combination of parts to be herein described and particularly pointed out in the appended claims.

The drawing shows, by way of example, a diagram according to the invention in which the motor to be protected is designed to drive a travelling crane.

Referring now to the drawing, A designates the current feeding line and B the trolley B ley. Connected in series with the trolley B are: the main current releasing coil C, the break of the overload circuit-breaker which consists of two stationary contact-points C¹ and C² and a movable contact member C³ actuated by the releasing coil C and adapted to bridge the two contact-points, the starting resistance D along with its sliding contact d¹ and the main current motor E E¹, the field winding E¹ of which is grounded by one of its ends. A current branch including a magnet coil C⁴ and a series resistance C⁴, is connected in parallel to the releasing coil C and the break C¹ C². The magnet coil C⁴ acts in the same sense as

the releasing coil C and it works on the same magnetic circuit as the releasing coil C. The exciting force of the magnet coil C⁴ is determined in such a manner as to be unable to open the overload circuit-breaker when same is in closed position, while it is adapted to hold the circuit-breaker, when opened, in its cut-out position contrary to the action of a tension spring C⁷ which engages the movable contact member C⁶. Connected in parallel with the main current motor E E¹ is a line K which contains another magnet coil C⁵ for the overload circuit-breaker and a series resistance G. The magnet coil C⁵ likewise acts on the same magnetic circuit and is wound in the same sense as the magnet coils C and C⁴.

The circuit K further comprises a contact device consisting of a conductor bar M and a sliding contact M¹. The sliding contact M¹ is attached to the frame N of the crane, while the conductor bar M is arranged parallelly to the track P of the crane-frame N and is of such length as to cause the sliding contact M¹ and the current bar M to remain in contact along the whole section of the track P on which the crane should travel at reduced speed.

In the position of the several parts, shown on the drawing, in which the sliding contact M¹ is in contact with the conductor bar M, in which the starting resistance D is partly switched off and in which the overload circuit-breaker is closed, the magnet coils C and C⁵ are energized so that the overload circuit-breaker possesses a comparatively high sensibility. The degree of this sensibility conforms to the strength of the excitation of the magnet coil C⁵. This excitation as well as the speed at which the crane is driven, depend upon the size of the switched-in portion of the starting resistance D.

If the speed of the crane is increased by switching off further steps of the starting resistance, the sensibility of the overload circuit-breaker will likewise be increased for the reason stated above. Now the size of the series resistance G is such as to cause the sensibility of the overload circuit-breaker to become so high, at a definite speed of the crane which is lower than the speed attainable with entirely cut-out starting resistance, that the circuit-breaker will

enter into action, provided, of course, that the contact device $M M^1$ is still closed.

As soon as the sliding contact M^1 leaves the conductor bar M in the further course 5 of the travelling motion of the crane, the magnet coil C^5 will be de-energized and the sensibility of the overload circuit-breaker will be accordingly reduced, so that the crane can be driven at a higher speed on 10 the track-sections situated beyond the section limited by the current bar M .

It will be obvious that it will be within the scope of the present invention to provide still other conductor bars to be connected in 15 parallel with the conductor bar M and arranged at other places of the crane-track P , such as for example at the ends of the track. Further, the circuit K which includes the magnet coil C^5 can be connected to include 20 the armature E alone instead of the motor $E E'$.

Claims:

1. In combination with an electric motor, a body propelled by said motor, a prescribed 25 track for said body, a main circuit in connection with said motor, an overload circuit breaker having a main current releasing coil in said circuit, an auxiliary coil for supplementing the action of said main current releasing coil, and means for automatically exciting said auxiliary coil at predetermined 30 points in the travel of said body.

2. In combination with an electric motor,

a body propelled by said motor, a prescribed track for said body, a main circuit in connection with said motor, an overload circuit breaker having a main current releasing coil, a shunt circuit in connection with said main circuit, an auxiliary coil for supplementing the action of said main circuit 40 current releasing coil disposed in said shunt circuit, and means for automatically opening or closing said shunt circuit at predetermined points in the travel of said body.

3. In combination with an electric motor, 45 a body propelled by said motor, a prescribed track for said body, a main circuit in connection with said motor, an overload circuit breaker having a main current releasing coil, a shunt circuit in connection with said 50 main circuit, an auxiliary coil for supplementing the action of said main circuit current releasing coil disposed in said shunt circuit and means for automatically opening or closing said shunt circuit at predetermined 55 points in the travel of said body, said means comprising a contact device disposed in said shunt circuit, one of the members of said contact device being arranged along said track and the other member of said contact device being attached to said body.

The foregoing specification signed at Essen, Germany, this 26th day of January, 1922.

WILLY SARTIG.
